BICYCLE HANDLEBAR GRIP OR SIMILAR ARTICLE

Sid Corlin, Chicago, Ill.
(P.O. Box 8731, Honolulu, Hawaii)

Filed Apr. 28, 1965, Ser. No. 84,989

Term of patent 14 years

(Cl. D90—11)

Fig. 1

Fig. 2

Fig. 3

FIGURE 1 is a side elevation of a bicycle handlebar grip or similar article showing my new design; FIGURE 2 is a top plan view; and

FIGURE 3 is a front end view thereof.

The broken lines indicating a handlebar in FIG. 1 are for illustrative purposes only.

I claim:

The ornamental design for a bicycle handlebar grip or similar article, as shown and described.
